UNITED STATES PATENT OFFICE.

OLIVE JOHNSON DE BLIEUX, OF CHICAGO, ILLINOIS.

LADY'S UNDERGARMENT.

1,110,749.

Specification of Letters Patent. Patented Sept. 15, 1914.

Application filed February 9, 1914. Serial No. 817,620.

To all whom it may concern:

Be it known that I, OLIVE JOHNSON DE BLIEUX, a citizen of the United States, residing at Chicago, in the county of Cook and 5 State of Illinois, have invented certain new and useful Improvements in Ladies' Undergarments, of which the following is a specification.

My invention relates to improvements in 10 ladies' under garments and more particularly to a one piece undershirt to be worn under the corset.

One of the objects of my invention is to 15 provide an undershirt which holds itself in position upon the body of the wearer without the aid of shoulder straps. Shoulder straps are very undesirable in many instances, particularly when an evening dress, which exposes the neck and shoulders, is 20 worn. In such cases, after the corset is in position holding the shirt in place, the shoulder straps are slipped over the arms and tucked in under the edge of the corset. Such an arrangement and procedure produces an 25 unsightly and uncomfortable bunching of the fabric at such points and is a very undesirable makeshift.

Another object of my invention is to provide an undershirt in which a band of elastic 30 tie ribbed knit fabric at the upper edge of the shirt performs not only the function of supporting the garment in proper position but also provides a support for the bust, adding materially to the comfort of the wearer.

Other and further objects of my invention 35 will become readily apparent from a consideration of the following description taken in conjunction with the drawings wherein:

Figure 1 is a perspective view, showing 40 my improved undershirt in use, and Fig. 2 is a side elevation of the same.

Referring to the drawings, numeral 10 in-

dicates in general a one piece undershirt formed of soft, elastic, textile fabric, such as is customarily used for garments of this nature in order that it may fit closely at the waist 11, over the hips 12, and breasts 13 and 14. The upper front edge of the garment passes over the breasts 13 and 14 on a line above their centers, and under the armpits. The upper edge is knitted into an elastic band of webbing 15, of approximately an inch and a half in width. This webbing overlying the breasts provides a support therefor and has sufficient elasticity to fit closely against the skin of the wearer and support the shirt in proper position. The top of the shirt is shaped so that the upper edge at the back extends horizontally approximately on a line with the armpits of a 60 wearer and at the front runs up and over the breasts at a point below that at which their outward curves merge into the straighter curves of the chest. The undershirt extends downward to a point 16 low 65 enough to come below the corset line and thus provides complete protection to the skin of the wearer from chafing by the corset.

Having described my invention, what I 70 claim is:

A lady's one piece armless undershirt, comprising a closely fitting body portion, terminating at its upper edge in a continuous knitted elastic band adapted to pass over the breasts and under the armpits of a 75 wearer.

In testimony whereof I hereunto set my hand in the presence of two subscribing witnesses.

OLIVE JOHNSON DE BLIEUX.
